UNITED STATES PATENT OFFICE.

CLARENCE W. COLEMAN, OF WESTFIELD, NEW JERSEY, ASSIGNOR TO
THE HALL SIGNAL COMPANY, A CORPORATION OF MAINE.

SIGNAL APPARATUS.

No. 818,744.

Specification of Letters Patent.

Patented April 24, 1906.

Application filed February 6, 1906. Serial No. 299,684.

To all whom it may concern:

Be it known that I, CLARENCE W. COLEMAN, a citizen of the United States, and a resident of Westfield, in the county of Union and State of New Jersey, have invented certain new and useful Improvements in Signal Apparatus, of which the following is a specification.

This invention relates to improvements in signal apparatus especially adapted for use on railways and capable of operation by means of a single electric motor and whereby a signal is enabled to assume three positions.

The invention seeks to provide such an apparatus in which great simplicity and compactness of the parts shall be obtained and in which there shall be great reliability and efficiency and little liability of derangement or improper working of the various parts. These objects are secured to a large extent by the particular arrangement of the parts whereby the power is applied to a thrust rod or piece which actuates the signal. This arrangement makes it possible to apply the power of the motor to the signal with a considerable economy of energy required to move the signal. It also makes it possible to employ a magnet or other device which shall be stationary and have the function of controlling the connection between the thrust rod or piece and the motor or motor-driven parts.

Some features of the invention are adapted for use in connection with a multiposition signal which assumes fewer than three positions, such as a two-position signal.

In the accompanying drawings, in which like numerals designate corresponding parts, the invention is illustrated in one of its various embodiments and as applied to a three-position signal.

Figure 1 is a side elevation of the apparatus looking in the direction of the arrow 1 in Fig. 4. Fig. 2 is a section along line 2 2 of Fig. 1 looking in the direction of the arrows. Fig. 3 is an assembled view with parts broken away, showing a three-position signal at caution or intermediate position. Fig. 4 is a front elevation of the apparatus. Fig. 5 is a detail front elevation showing a modification of the actuating connection to operate the signal. Fig. 6 is a side elevation looking in the direction of the arrow 6 in Fig. 4. Fig. 7 is a horizontal section along line 7 7 in Fig. 4

looking in the direction of the arrows. Fig. 8 is a detail in elevation and partly in section, 55 showing a cam-piece in coöperation with its thrust-piece. Fig. 9 is a similar view, but looking in the direction of arrow 1 in Fig. 4 and showing in dotted lines the power-gear 10 and successive positions of the cam-piece. 60 Fig. 10 is a plan view in section along line 10 10 of Fig. 8 looking in the direction of the arrows. Fig. 11 is a plan view, partly in section, along line 11 11 of Fig. 8 looking in the direction of the arrows. Fig. 12 is a diagram 65 showing the signals and circuits for two blocks of a railway.

Referring now to the particular embodiment of the invention as shown in the drawings, the frame of the machine consists of the 70 base 1, back ribs 2 and 3, upper yoke 4, and stirrup 5.

6 is an electric motor which drives gear-wheel 7, carried on the shaft 8 on which is mounted pinion 9, meshing with the driving 75 gear-wheel 10. The shaft 8 is supported by the uprights 11 and 12, bolted to the stirrup 5 at their lower ends and bolted at their upper ends to the yoke 4. These uprights 11 and 12 are provided with bearings for the 80 shaft 13, which carries the driving-gear 10.

14 is a three-position signal carried by the post 15 and operated through the signal-actuating connection 16, to which power is applied by the thrust-pieces 17 and 18, respectively, which may have the form of a signal-rod 16, as shown in Figs. 1, 2, 3, and 6, or it may be in the form of a cord or flexible connection 64, as shown in Fig. 5. In this latter case the cord is connected at its upper end 90 with the signal on the blade's side of the signal's pivot and at its lower end passes under a guide-roller 55 on the main frame. These thrust-pieces coöperate through the medium of the floating lever 19, which is connected 95 by the pivot 20 with the signal-actuating connection and is guided in its up-and-down movement by suitable guides or rollers 21, moving on guideways 22, formed on casings 23 and 24, surrounding the upper ends of the 100 thrust-pieces 17 and 18, respectively. The ends of the floating lever 19 are connected with the thrust-pieces 17 and 18 by links 25 and 26, respectively, which are supported on brackets 27 and 28, fixed to the cam-blocks 105 33 and 34, respectively. The lower ends of

these thrust-pieces carry dash-pot cylinders 29 and 30, respectively, to which they are directly connected, the axes of the dash-pots being in lines parallel with the lines of vertical movement of their respective thrust-pieces 17 and 18.

31 and 32 are cam-pieces to move the thrust-pieces 17 and 18 and are illustrated as being oscillating. These pieces 31 and 32 may be mounted in any suitable manner, but in the best form and as shown in the drawings they are pivotally mounted at their ends on brackets 33 and 34, which in turn are fixed to the thrust-pieces 17 and 18, respectively. 15 These oscillating pieces serve as cam-pieces and are respectively engaged by cams 35 and 36, fixed on opposite sides of the gear 10. 37 is a catch pivoted to the end of the cam-piece 31 opposite its pivot connection and 20 spring-pressed toward the thrust-piece 17 by the spring 38 and is designed to engage the releasable latch 39, formed on the end of the lever 40, which is pivoted at 41 to the projecting end of the bracket 33. The lever 40 25 is provided with a roller 42 at its lower end. The catch 37 on the end of the cam-piece 31 engages the latch 39 to move the thrust-piece 17 upward until the catch 43, pivoted to a vertical extension of the bracket 33 and outwardly 30 spring-pressed by the spring 44, engages with the locking-dog 45, rigid with and operated by the lever 46. This dog 45 then serves to lock the thrust-piece through the medium of the catch 43 in its upper position. 35 The lever 46 is pivoted at its upper end to the frame at 47 and swings back and forth in a vertical plane, but is normally held against the roller 42 by means of a counterweight 48. When the lever 46 is held inward by some 40 force stronger than that exerted by the counterweight 48 against the roller 42 and the cam-piece 31 is moved upward the thrust-piece and coöperating latching means is moved upward, while the roller 42 rolls along 45 the face of the lever 46 and maintains the latch 39 in engagement with the catch 37. When the thrust-piece has reached its upper position, the lever 46, through the medium of the dog 45, serves to hold the thrust-piece 50 locked in its elevated position, although the cam-piece 31 may have ceased to exert a lifting pressure on the thrust-piece. It will be seen, therefore, that the lever 46 controls the engagement of the cam-piece 31 with the latch 39 and also controls the device or means for locking the thrust-piece in its elevated position into which it is moved by the cam-piece.

In the preferred arrangement of the mechanism the cam-piece 31 is operated by a cam, and for this purpose has a cam-face or flange 49, against the under surface of which the cam engages.

35 is the cam which coöperates with the

cam-piece 31. In its best form and as shown in the drawings the cam 35 is in the form of a roller carried on a spoke of the power-wheel 10.

When the thrust-piece 17 is in its lower position, cam-piece 31 is normally in its lower position, with its cam-engaging part 49 resting on the cam 35, the catch 37 being below latch 39 about an eighth of an inch to allow for play.

51 is an armature at the lower end of the controlling-lever 46 and normally hangs in proximity to the poles of the controlling-magnet 52.

In the operation of the parts above described the magnet 52 is energized to hold the lever 46 inward, and the motor is started. Lever 46 bears against roller 42, as above described. As the power-wheel 10 travels in the direction of the arrow shown in Figs. 1, 6, and 9 cam 35 engages with the cam-face 49 on the cam-piece 31 and carries cam-piece 31, bracket 33, and the thrust-piece 17, together with the coöperating latch, upward to the position shown in Figs. 8 and 9, latch 49 during their movement being locked in engagement with catch 37. During this movement the cam 35 moves from one end of the cam-face 49 to the other, as illustrated in dotted lines in Fig. 9, and then out from under the cam-piece, whereupon the motor stops. When the cam 35 disengages the cam-piece, the thrust-piece is supported by the dog 45, which engages catch 43, spring 44 having permitted this catch to snap past the dog 45. When the lever 46 is released, as by deenergizing magnet 52, the weight on the thrust-piece presses downward on the dog 45, and overcoming the counterweight 48 causes the controlling-lever 46 to swing outward, whereupon the thrust-piece, with the parts carried thereby, and the bracket 33, with the parts carried thereby, all return to the lower position.

If for any reason the magnet 52 should be deenergized and the motor stopped before the cam 35 had passed from under cam 31, and after the thrust-piece had been more or less elevated, nevertheless the thrust-piece would return to its initial position, since the weight of the thrust-piece would cause the lever 40, already released from lever 46, to swing out of engagement with catch 37. In this case the cam-piece 31 would be swung upward on its pivot 50 by cam 35 until cam-piece 31 cleared cam 35, whereupon cam-piece 31 would swing back on its pivot and come to rest on the bracket 33 and with catch 37 beneath latch 39. It will therefore be seen that the thrust-piece has a return movement independent of the cam 35 and independent of the cam-piece 31. Thus it will be seen that by this arrangement the signal after having been moved all the way or only just part way to "caution" may return to "danger" at once.

as soon as magnet 52 is deenergized and without regard to the position of the motor or the power-wheel 10 or cam 35.

Magnet 52 has a second armature which 5 operates circuit-controller 54 to control the circuit of the motor, as will hereinafter appear. When the magnet is energized, the circuit-controller 54 is closed, and when it is deenergized the circuit-controller opens.

10 56 is a rod pivoted at its upper end to an L-shaped lever 57, which is pivoted at 58 to the yoke 4. The rod 56 is pivotally connected at its lower end with a crank-shaft 59, which operates circuit-breakers 60, 61, and 15 62. 63 is a roller carried on the bracket 27. When the thrust-piece 17 rises to the limit of its upward movement and puts the signal to "caution," roller 63 comes against the upper 20 end of the lever 57, thereby elevating rod 56 and opening the circuit-breakers 60 and closing the circuit-breakers 61 and 62. When the magnet 52 is deenergized to permit the thrust-piece 17 to move downward, roller 63 comes against the depending end of lever 57, 25 turning it back on its pivot to its former position, and thereby lowering rod 56, so as to close the circuit-breaker 60 and open circuit-breakers 61 and 62.

The mechanism coöperating with the 30 thrust-piece 18 for moving the signal from "caution" to "safety" is similar to that described as coöperating with the thrust-piece 17 and need not be specifically described.

35 36 is the cam-roller coöperating with the cam-piece 32 for thrust-piece 18. It is fixed on the power-wheel 10 on the opposite side from the cam 35 and one hundred and eighty degrees therefrom.

40 66 is the latch pivoted on the thrust-piece 18, corresponding to the latch 39 pivoted on the thrust-piece 17. 67 is the lever corresponding with the lever 46 and carrying the armature 65 at its lower end controlled by the magnet 68. 69 is the locking-dog on the 45 end of the lever 67, corresponding with the dog 45 on lever 46 and to lock the thrust-piece 18 in its upper position and arranged to engage with the catch 70. 71 is a circuit-breaker rod corresponding with the rod 56 50 and pivoted at its upper end to lever 72, corresponding to lever 57.

73 is the roller carried by the depending lever of the latch 66, corresponding to roller 42 and operating to engage the lever 67. Rod 55 71 operates the crank-shaft 74. 76 is a circuit-controller operated by magnet 68. After the motor has elevated thrust-piece 17 to put the signal to "Caution" the motor is free to continue its rotation to elevate the thrust-piece 18. This latter operation will take 60 place when magnet 68 is energized. When this happens, power-wheel 10 continues its rotation and cam 36 engages cam-piece 32, which piece connects with thrust-piece 18 to 65 elevate the same and move the signal from

"caution" to "safety." When the magnet 52 is deenergized, thrust-piece 17 is released and falls to the lower position, and the signal moves from "safety" to "caution." When both magnets 52 and 68 are deenergized, 70 both thrust-pieces return to their lower positions, and the signal continues its movement to "danger." Up to this point the operation and control of the movements of the individual thrust-pieces has been described. 75 The object of the movement of these thrust-pieces is to move the signal-actuating connection or signal-rod a fractional amount, and thereby step the multiposition signal from one indicating position to another. 80

The transmission of motion from the thrust-pieces to the signal-actuating connection is through the medium of the floating lever 19. As one thrust-piece, as 17, rises the other thrust-piece 18, through the medium of the 85 link 26, serves as a fulcrum for the lever 19, pivot 20 of which is raised between the vertical guideways 22 a fractional amount. When the thrust-piece 17 has been moved to the limit of its upward motion, it is locked in 90 that position.

The companion thrust-piece 18, which is operated similarly to thrust-piece 17, now may move upward and through the medium of the link 26 again actuates the lever 19 and 95 in this operation employs the thrust-piece 17 as its fulcrum through the medium of the link 25. This movement of the thrust-piece 18 raises the pivot 20 a second fractional distance, and therefore the signal a corresponding fractional amount. By the locking of the thrust-piece 18 in its upper position the pivot 20 and the signal-rod 16 or cord 64 is 100 locked in this position. The connection of the signal-rod 16 or cord 64 with the signal-blade is such that the upward movement of the thrust-pieces moves the signal first from "danger" to "caution" and second from "caution" to "safety" against the counterweight of the signal. As one or both of the 110 thrust-pieces may now be released, the signal-operating connection 16 returns to its initial position by fractional movements similar to the fractional movements during its first motion, but in the opposite direction. 115 By releasing both thrust-pieces 17 and 18 simultaneously the pivot 20 would immediately return, due to the counterweight of the signal, to its lower position, which in the embodiment illustrated would throw the signal 120 to "danger," or first one thrust-piece might be released, the signal going to "caution," and then the other thrust-piece might be released, the signal going to "danger."

In Fig. 12, 77 and 78 are two blocks of a 125 railway provided with signals 14 and 80, respectively, such as heretofore shown and described. The signals are arranged to operate on the normal safety principle. They may, however, be arranged to operate on the nor- 130

mal danger principle, if desired. They are supposed to stand at the entrance to their respective blocks. The motor-magnets and other parts associated with the three-position signals 14 and 80 in Fig. 12 have the same reference-numerals as the corresponding parts in the other figures. 81 is the track-magnet for block 77. 82 is the track-magnet for block 78. The circuit of the controlling-magnet 52 is from battery 83, circuit-controller 84, wire 85, wire 86, magnet 52, and wires 87 and 88 back to battery 83. Since the signals are normally at "safety," this circuit through the magnet 52 and which is controlled by track-magnet 81 is normally closed. The circuit of the motor 89 for operating signal 14 is from battery 83, wire 90, circuit-controller 54, wire 91, circuit-breaker 60, wire 92, motor 89, wire 88, back to battery 83. This motor-circuit is the circuit which causes the movement from "danger" to "caution" by elevating thrust-piece 17. The circuit of the motor which causes the movement from "caution" to "safety" is from battery 83, through wire 90, circuit-controllers 54 and 76, wire 93, circuit-breaker 75, wires 94 and 92, motor 89, wire 88 back to battery 83. The normally closed circuit of the signal-magnet 68 is from battery 95 of the following block, wire 96, circuit-controller 97, wire 98, circuit-breaker 99, wire 100, circuit-breaker 60, wire 101, magnet 68, wires 102, 87, 88, and 103 back to battery 95.

The operation of the circuits is as follows: The thrust-pieces are normally locked in their elevated positions, holding the signals at "safety." When a train enters block 77, it shunts track-magnet 81 and opens at 84 the circuit of the controlling-magnet 52. When controlling-magnet 52 is thus deenergized, it unlocks the locking-dog, holding the thrust-piece 17 in its elevated position, allowing the thrust-piece 17 and the signal 14 to move downward by the falling of the signal's counterweight. The falling of this thrust-piece 17 also opens the circuit-controller 62, which breaks the circuit through controlling-magnet 68, previously traced. When signal-magnet 68 is thus deenergized, its armature releases the locking-dog 69, holding thrust-piece 18 in elevated position. Then the thrust-piece 18 falls and allows the signal 14 to continue its movement to "danger," at the same time closing the circuit-breaker 75. When the thrust-piece 17 falls, the circuit-breaker 61 is also opened and the circuit-breaker 60 is closed. When the train passes out of block 77 into block 78, magnet 81 is energized so as to close circuit-controller 84. This energizes the circuit of the signal-magnet 52, as heretofore traced. Magnet 52 thereupon closes circuit-controller 54 and completes the circuit of the motor heretofore traced through circuit-controller 54 and circuit-breaker 60. The motor thereupon op-

erates to move the thrust-piece 17 to its elevated position, where it is locked by means of the latching-dog previously described, the signal 14 being thus positively moved to "caution" by the operation of the motor, and the circuit-breakers 61 and 62 are restored to their normally closed positions and the circuit-breaker 60 is opened, thereby stopping the motor. When the train enters block 78, it also shunts track-magnet 82, which opens circuit-controller 97 and puts the signal 80 for block 78 to "danger" in the same way as was described with reference to the signal 14. Circuit-controller 97 and circuit-breaker 99 are in the circuit of the signal-magnet 68, and this circuit is also opened at circuit-breaker 99 as soon as signal 80 for block 78 goes to "caution." Thus although the circuit of magnet 68 has been closed at 62 it remains deenergized, and signal 14 is held at "caution" as long as the train is in block 78. When the train passes out of block 78, circuit-controller 97 closes and signal 80 is put to "caution" in the same way as has been described with reference to signal 14, thereby closing circuit-breaker 99. This completes the circuit of signal-magnet 68, which then closes circuit-controller 76 and completes the circuit through the motor 89 to elevate the thrust-piece 18. This circuit, as already traced, extends through circuit-controllers 54 and 76 and circuit-breaker 75, which latter was closed when the piece 18 fell. Thereupon the motor operates positively to put the signal 14 to "safety" and to lock it thereby means of the locking-dog 69 engaging the thrust-piece 18, as heretofore described. When the signal reaches safety position, the motor-circuit is broken at circuit-breaker 75 and the motor stops.

While this apparatus is herein shown and described in what is believed to be its best form, it will be understood that the details of the mechanism may be variously modified without departing from the scope of the invention. It will be further understood that the apparatus may successfully be associated in conjunction with various arrangements preferred for ordinary installations.

The modification illustrated in Fig. 5, which employs a flexible actuating connection for the signal, has the peculiar advantage of providing a downward pull on the working end of the signal connection by means of an upward movement of a thrust-piece, thus making it possible to employ a flexible signal connection without changing the mode of operation either of the thrust-pieces or of the various motor-driven parts.

What I claim, and desire to secure by Letters Patent, is—

1. In a multiposition signal, the combination of a signal-actuating connection; a plurality of cam-pieces to actuate said signal connection; a cam to engage each cam-piece

- and move said signal connection a fractional distance, said signal connection having a return movement independent of the cam-pieces.
2. In a multiposition signal the combination of a flexible signal connection; a plurality of cam-pieces to actuate said flexible signal connection; a cam to engage each cam-piece and move said signal connection a fractional distance; said signal connection having a return movement independent of the cam-pieces.
3. In a three-position signal, the combination of a signal-actuating connection; two cam-pieces to actuate said signal connection; a cam to engage each cam-piece and move said signal connection a fractional distance, said signal connection having a return movement independent of the cam-pieces.
4. In a three-position signal, the combination of a flexible signal connection; two cam-pieces to actuate said signal connection; a cam to engage each cam-piece and move said signal connection a fractional distance, said signal connection having a return movement independent of the cam-pieces.
5. In a multiposition signal, the combination of a plurality of thrust-pieces; a cam-piece to engage each thrust-piece; a cam to engage each cam-piece, and move its thrust-piece, each thrust-piece having a return movement independent of its cam-piece; a signal-actuating connection; and means connecting the thrust-pieces and said signal-actuating connection to move said connection a fractional distance upon the movement of each thrust-piece.
6. In a multiposition signal, the combination of a plurality of thrust-pieces; a cam-piece to engage each thrust-piece; a cam to engage each cam-piece and move its thrust-piece, each thrust-piece having a return movement independent of its cam-piece; a flexible signal connection and means connecting the thrust-pieces and said signal connection to move said signal connection a fractional distance upon the movement of each thrust-piece.
7. In a three-position signal, the combination of two thrust-pieces; a cam-piece to engage each thrust-piece; a cam to engage each cam-piece and move its thrust-piece, each thrust-piece having a return movement independent of its cam-piece; a signal-actuating connection; and means connecting the thrust-pieces and said signal-actuating connection to move said signal connection a fractional distance upon the movement of each thrust-piece.
8. In a three-position signal, the combination of two thrust-pieces; a cam-piece to engage each thrust-piece; a cam to engage each cam-piece and move its thrust-piece, each thrust-piece having a return movement independent of its cam-piece; a flexible connection; and means connecting the thrust-pieces and said signal-actuating connection to move said signal connection a fractional distance upon the movement of each thrust-piece.
9. In a three-position signal the combination of a floating lever; a signal-actuating connection pivoted to said lever between its ends; two thrust-pieces; means connecting the ends of said lever with the thrust-pieces; a cam-piece to engage each thrust-piece; and a cam to engage each cam-piece and move its thrust-piece, each thrust-piece having a return movement independent of its cam-piece.
10. In a three-position signal the combination of a floating lever; a signal-actuating connection pivoted to said lever between its ends; two thrust-pieces; links connecting the ends of said lever with the thrust-pieces; a cam-piece to engage each thrust-piece; and a cam to engage each cam-piece, and move its thrust-piece, each thrust-piece having a return movement independent of its cam-piece.
11. In a three-position signal, the combination of a floating lever; guiding means for said lever; a signal-actuating connection pivoted to said lever between its ends; two thrust-pieces; means connecting the ends of said lever with the thrust-pieces; a cam-piece to engage each thrust-piece; and a cam to engage each cam-piece to move its thrust-piece, each thrust-piece having a return movement independent of its cam-piece.
12. In a three-position signal; the combination of a floating lever; a flexible signal connection; a pivot connection for said signal connection between the ends of said lever; guides on said pivot connection; parallel guideways for said guides; two thrust-pieces; means connecting the ends of said lever with the thrust-pieces; a cam-piece to engage each thrust-piece; and a cam to engage each cam-piece, and move its thrust-piece, each thrust-piece having a return movement independent of its cam-piece.
13. In a three-position signal, the combination of a floating lever; a flexible signal connection; a pivot connection for said signal connection between the ends of said lever; guide-rollers on said pivot connection; parallel guideways for said guide-rollers; two thrust-pieces; links connecting the ends of said lever with the thrust-pieces; a cam-piece to engage each thrust-piece; and a cam to engage each cam-piece and move its thrust-piece, each thrust-piece having a return movement independent of its cam-piece.
14. In a multiposition signal, the combination of a signal-actuating connection; a plurality of cam-pieces to actuate said signal connection; a cam to engage each cam-piece; and move said signal connection a fractional distance, said signal connection having a return movement independent of its cam-pieces; and a single motor for actuating said cams.

15. The combination of a thrust-piece; a pivoted cam-piece to engage said thrust-piece; and a cam to engage the cam-piece to move the thrust-piece, the thrust-piece having a return movement independent of the cam-piece.
16. The combination of a thrust-piece; a bracket fixed thereto; a cam-piece pivoted at one end to said bracket and adapted to engage said thrust-piece with its opposite end; and a cam to engage said cam-piece and move the thrust-piece, said thrust-piece having a return movement independent of the cam-piece.
- 15 17. The combination of a thrust-piece; a bracket fixed thereto; a cam-piece pivoted at one end to said bracket; a catch on the opposite end of the cam-piece to engage said thrust-piece; and a cam to engage said cam-piece and move the thrust-piece, said thrust-piece having a return movement independent of the cam-piece.
- 25 18. The combination of a thrust-piece; a bracket fixed thereto; a cam-piece pivoted at one end to the bracket; a catch on the opposite end of the cam-piece; a releasable latch on said thrust-piece to be engaged by said catch; a cam to engage said cam-piece and move the thrust-piece, said thrust-piece having a return movement independent of said cam-piece.
- 35 19. The combination of a thrust-piece; a bracket fixed thereto; a cam-piece pivoted at one end to the bracket; a catch on the opposite end of the cam-piece; a releasable latch on said thrust-piece to be engaged by said catch; a lever with a stationary fulcrum to hold said latch in engagement with said cam-piece; a cam to engage said cam-piece to move the thrust-piece, said thrust-piece having a return movement independent of said cam-pieces.
- 45 20. The combination of a thrust-piece, with a bracket fixed thereto; a cam-piece pivoted at one end to the bracket; a catch on the opposite end of the cam-piece; a releasable latch on said thrust-piece to be engaged by said catch; a lever with a stationary fulcrum to hold said latch in engagement with said cam-piece catch; a magnet controlling said lever; and a cam to engage said cam-piece to move the thrust-piece, said thrust-piece having a return movement independent of said cam-piece.
- 55 21. The combination of a thrust-piece; with a bracket fixed thereto; a cam-piece pivoted at one end to the bracket; a catch on the opposite end of the cam-piece; a releasable latch on said thrust-piece to be engaged by said catch; a lever with a stationary fulcrum to engage said latch to hold it in engagement with said cam-piece catch; a cam to engage said cam-piece to move the thrust-piece; a magnet controlling said lever, which lever, when released allows the cam-piece to swing on its pivot thereby giving the thrust-piece an independent return movement from any position.
- 60 22. The combination of a thrust-piece; with a bracket fixed thereto; a cam-piece pivoted at one end to the bracket; a catch on the opposite end of the cam-piece; a releasable latch on said thrust-piece to be engaged by said catch; a lever with a stationary fulcrum to hold said latch in engagement with said cam-piece catch; a magnet controlling said lever; means on said lever to lock the thrust-piece at the limit of its initial movement until released by said magnet; and a cam to engage said cam-piece to move the thrust-piece, said thrust-piece having a return movement independent of said cam-piece.
- 70 23. The combination of a thrust-piece, with a bracket fixed thereto; a cam-piece pivoted to said bracket; a releasable latch on said thrust-piece to engage with said cam-piece; a rotatable wheel; and a cam on said wheel to engage said cam-piece and move said thrust-piece, said thrust-piece having a return movement independent of said cam-piece when said latch releases said cam-piece.
- 75 24. The combination of a thrust-piece; an oscillating piece; means for engaging together said oscillating piece and thrust-piece; a stationary magnet controlling said means; and a cam for moving said oscillating piece and thrust-piece.
- 80 25. In a multiposition signal, the combination of a signal-actuating connection; a plurality of pivoted cam-pieces to actuate said signal connection; a cam to engage each cam-piece and move said signal connection a fractional distance, said signal connection having a return movement independent of the cam-pieces.
- 85 26. In a three-position signal, the combination of a flexible signal connection; two pivoted cam-pieces to actuate said signal connection; a cam to engage each cam-piece and move said signal connection a fractional distance, said signal connection having a return movement independent of each cam-piece.
- 90 27. In a multiposition signal, the combination of a plurality of thrust-pieces; a pivoted cam-piece to engage each thrust-piece; a cam to engage each cam-piece and move its thrust-piece, each thrust-piece having a return movement independent of its cam-piece; a flexible signal connection and means connecting the thrust-pieces and said signal connection to move said signal connection a fractional distance upon the movement of each thrust-piece.
- 95 28. In a three-position signal, the combination of a floating lever; guiding means for said lever; a signal-actuating connection pivoted to said lever between its ends; two thrust-pieces; means connecting the ends of said lever with the thrust-pieces; a pivoted
- 100 105 110 115 120 125 130

cam-piece to engage each thrust - piece and move the signal, each thrust-piece having a return movement independent of its cam-piece.

29. In a signal apparatus, motor operated and upwardly-movable actuating means; a flexible signal connection connected with said means at one end and with the signal at its other end; and a fixed guide for said flexible connection whereby a downward movement of the signal end of said flexible connection to move the signal is caused by an upward movement of said actuating means.

30. In a signal apparatus a signal-post; a signal-blade pivoted to said post at one side thereof; power-operated and upwardly-movable actuating means; a flexible signal connection attached at one end to said blade on the post side of its pivot connection, and at its other end to said actuating means; and a fixed guide for said flexible connection, whereby the direction of said flexible connection is changed and an upward movement of said actuating means causes a downward movement of the signal end of said flexible connection to move said blade.

31. In a multiposition signal apparatus, the combination of a signal-actuating connection; a plurality of cam-pieces to actuate said signal connection; a cam to engage each cam-piece and move said signal connection a fractional distance, said signal connection having a return movement independent of the cam-pieces.

32. In a three-position signal apparatus, the combination of a signal-actuating connec-

tion; two cam-pieces to actuate said signal connection; a cam to engage each cam-piece and move said signal connection a fractional distance, said signal connection having a return movement independent of the cam- 40 pieces.

33. In a three-position signal apparatus, the combination of a signal-actuating connection; two cam-pieces to actuate said signal connection; a rotatable power-wheel; a cam 45 fixed to each side of said wheel to engage each cam-piece and move said signal connection a fractional distance, said signal connection having a return movement independent 50 of the cam-pieces.

34. In a three-position signal apparatus, a motor; a signal-actuating floating lever upwardly movable at each end by said motor; a signal-blade; a guide fixed below said floating lever; a flexible signal connection attached at 55 one end to said floating lever intermediate the ends of said lever, passing down around said guide and attached at its other end to said signal; whereby an upward movement of either end of said lever causes a downward 60 pull on the signal connection at the end attached to the signal and moves the signal.

In testimony whereof I have signed my name to this specification in the presence of two subscribing witnesses.

CLARENCE W. COLEMAN.

Witnesses:

LEONARD DAY,
IDA G. GILMORE.
